UNITED STATES PATENT OFFICE.

THOMAS HAWKINS, OF LONDON, ENGLAND.

SAFETY-FASTENER FOR ENVELOPS.

SPECIFICATION forming part of Letters Patent No. 655,230, dated August 7, 1900.

Application filed May 8, 1899. Serial No. 715,996. (No model.)

To all whom it may concern.

Be it known that I, THOMAS HAWKINS, a citizen of the United States of America, residing at 40 Marchmont street, Russell Square, London, England, have invented certain new and useful Improvements in Envelops and the Like and in Safety-Fasteners Therefor, of which the following is a specification.

My invention relates to improvements in envelopes and the like and in safety-fasteners therefor; and the objects of my improvements are to prevent fraudulent opening of the envelop or tampering with the contents without such fraud or tampering becoming known.

The great advantage of my invention is the perfect security of the fastening, which cannot possibly be undone after it is once secured, the only way of opening the envelop or the like being to cut or tear the paper or other material of which it is composed.

Other advantages which my invention possesses are that it is cheap to manufacture and both easy and certain in its action without being at all unsightly in appearance.

I carry out my invention as follows, reference being made to the accompanying drawings, in which—

Figure 1 is a section of the safety-fastener before the parts are secured, one portion being fixed to the outer flap of the envelop or the like and the other portion to the inner or overlapping flaps or folds. Fig. 1^a shows three parts of the fastener separated. Fig. 2 is a section of the safety-fastener when closed and keeping the flaps of the envelop or the like secured. Fig. 3 is a section of an alternative form of the safety-fastener. Fig. 3^a shows four separate parts of the complete fastener in this alternative form. Fig. 4 is a section of the alternative form of the safety-fastener when keeping the flaps of the envelop or the like closed. Figs. 5 and 6 are views of an envelop containing my present improvements, showing the fastener open and closed, respectively.

Similar letters refer to similar parts throughout the several views.

The essential features of my invention consist, first, in perforating the meeting flaps or equivalents of the envelop or the like; sec-

ondly, of a hollow rivet or eyelet attached to one of the flaps; thirdly, an annular disk or washer secured to the other flap or folds; fourthly, an anvil-plate, and, fifthly, means for insuring the spreading of the edge of the rivet underneath the annular disk or washer when pressed, thereby riveting the two parts of the envelop or the like together.

My invention can be carried out in various forms; but in all cases the outer flap and also the inner flaps or folds are punched (preferably during the process of manufacture) each with a small hole, (or more than one,) the hole of the outer flap registering accurately with the hole of the inner flap when folded down. These holes may or may not be eyeleted, as desired; but for ordinary purposes it would be unnecessary.

According to my invention I take a small metal hollow rivet, somewhat like a lace-boot eyelet, consisting of a tubular portion A and a flange B and pass it through the hole of the (preferably) outer flap C, where it is held in place by a canvas or other suitable backing D of sufficient size to more than cover said flange. This constitutes one portion of my fastener. The other portion of my fastener, attached to the other flap of the envelop, is shown in several forms. According to the forms shown by Figs. 1, 1^a, and 2 the metal plate E has a raised tapered portion E' in its center and acts both as an anvil and as a guide and spreader for the rivet A when the two are pressed together. Before applying the anvil-plate E, I pass over it an annular disk or washer F and then secure them both in the envelop by a paper or other backing G, the raised portion E' projecting slightly through the hole of the flap or folds of the envelop or the like.

The anvil-plate E and washer F are preferably stamped out of sheet metal, being at the same operation dished around the edges, as shown more clearly in Fig. 2, so as to facilitate fitting them together. The spreader E' may be open at the top or not, as desired. The washer F is raised or dished around the edge of its hole, as shown, so as to allow sufficient space for the edge of rivet A to spread underneath same when forcibly pressed down over the spreader E'. The three metal parts

of the fastener are shown separated in Fig. 1^a, the rivet A being preferably stamped from some very ductile or thin metal. I intend that the envelop shall be supplied for use 5 with the parts already fixed therein, as shown by Fig. 1. In order to fasten the envelop, it is simply necessary to close the flaps together (the tube A being thus brought down upon the guide and spreader E') and press down 10 upon the canvas or equivalent D with a hard object, such as a coin. The bottom edge of the tube A will then easily spread and become directed underneath the washer F, which being much larger than the hole in the flap or 15 folds will effectively prevent the rivet from being withdrawn.

According to the forms shown in Figs. 3, 3^a, and 4 the guide and spreader E² is an independent short tube separate from the anvil H, which in this case may be a small flat 20 piece of thin metal dished at the edge. The guide E² is slightly smaller at its upper edge than the tube A, but widens out at the bottom into a curve, so as to cause the edge of 25 tube A, when pressed over same, to split and spread horizontally under the washer F.

The envelop as it appears with my improved fastener attached is shown open and closed in Figs. 5 and 6.

One or more of my safety-fasteners may be 30 used for one envelop, according to desire.

Having now described my invention, what I claim as new, and desire to secure by Letters Patent, is—

1. A safety-fastener consisting of a hollow 35 rivet or eyelet fastened to one of the flaps or folds of an envelop and an anvil-plate with raised center secured to the opposite flap or fold at the point where they meet when folded down said anvil-plate carrying an annular 40 disk or washer surrounding said raised center substantially as described and as shown by the accompanying drawings.

2. A safety-fastener consisting of a hollow rivet or eyelet fastened to one of the flaps or 45 folds of an envelop and the combination of an anvil-plate, a spreader, and an annular disk or washer, said combination being secured to the opposite flap or fold at the point where they meet when folded down substantially as described and as shown by the accompanying drawings.

In witness whereof I have hereunto set my hand in presence of two witnesses.

THOMAS HAWKINS.
